FIG. 1

FIG. 2

FIG3

FIG4

FIGURE 1 is a front elevational view of a pipe organ, showing my new design;

FIGURE 2 is a right end elevational view;

FIGURE 3 is a left end elevational view; and

FIGURE 4 is a rear elevational view thereof.

This is a division of design application Ser. No. 5,607, filed Jan. 30, 1967, now abandoned, which was a continuation-in-part of design application Ser. No. 2,685, filed June 15, 1966, which issued as Design Patent 206,826 on Jan. 31, 1967.

The dominant features of the design according to the invention reside in the portions shown in solid lines.

I claim:

The ornamental design for a pipe organ, substantially as shown and described.
